UNITED STATES PATENT OFFICE.

CHARLES E. LIGHTNER, OF SAN ANTONIO, TEXAS.

DESIGN FOR OVERALLS.

SPECIFICATION forming part of Design No. 25,932, dated August 11, 1896.

Application filed July 14, 1896. Serial No. 599,193. Term of patent 14 years.

To all whom it may concern:

Be it known that I, CHARLES EUGENE LIGHTNER, a citizen of the United States, residing at San Antonio, in the county of Bexar and State of Texas, have invented and produced a new and original Design for Overalls, of which the following is a specification, reference being had to the accompanying drawing, which shows a perspective view of overalls embodying my design.

The leading feature of my design consists

in the front extension or apron A, which is divided centrally and longitudinally, as shown at a.

What I claim is—

The design for overalls as shown and described.
